UNITED STATES PATENT OFFICE.

THOMAS BOLTON GIFFEN AND JOHN BISSETT, OF RUTHERGLEN, SCOTLAND.

STARCHING-MACHINE.

SPECIFICATION forming part of Letters Patent No. 648,765, dated February 20, 1900.

Application filed September 18, 1897. Serial No. 652,152. (No model.)

To all whom it may concern:

Be it known that we, THOMAS BOLTON GIFFEN and JOHN BISSETT, subjects of the Queen of Great Britain, and residents of Rutherglen, 5 in the county of Lanark, Scotland, have invented certain new and useful Improvements in Starching-Machines, of which the following is a specification.

This invention relates to apparatus more 10 particularly for starching the fronts and cuffs of shirts and similar articles, also collars, cuffs, and shirt-fronts, though it may be applied to washing or other purposes for which it may be found applicable. It is designed 15 to provide apparatus which will act upon the articles without subjecting them to a rubbing action or friction, and thus avoid wear and lengthen the life of such articles. It will be 20 fully described with reference to the accompanying drawings.

Figure 1 is a longitudinal sectional elevation on line xx , Fig. 3; Fig. 2, a longitudinal sectional elevation on line yy , Fig. 3; Fig. 3, a plan with cover removed; Fig. 4, a plan of 25 cover and lid; Fig. 5, a sectional elevation of worm-gearing; Fig. 6, a detail of screw for holding on the cover; Fig. 7, a detail of front of box, showing the opening a and panel B.

A water-tight box or receptacle A is constructed of cast-iron or other suitable material, with an opening a in the front side to receive such parts of the articles as are to be treated. The opening a is closed by a sliding panel B, which closes down upon the articles 35 which project therethrough and prevents the escape of liquor during the operation.

Inside the water-tight box A we fit several (preferably three) paddles or plungers C D, which receive a reciprocating or oscillating 40 movement from any suitable source of motion. The paddles or plungers D when in operation approach to and recede from one another, alternately compressing or squeezing the clothes between them and then releasing 45 them, thus causing them to rapidly absorb or become impregnated with the starch or other liquor.

The plunger or paddle C reciprocates to and fro, and its shank or outer end c passes 50 through guideway E and is connected by the connecting-rod F, jointed to it by the pin f , to

the crank-pin g on the rotating disk G, by which the desired movement is imparted.

The plungers or paddles D are affixed to the rods or arms d , which are pivoted on pins 55 d' , screwed into the top and bottom of the box A, upon which they can oscillate to and fro. The rods d are connected to the reciprocating shank c of the plunger C by connecting-rods E', pivoted at one end to the shank c and at 60 the other end to the rods d , whereby the reciprocating movement of the plunger or paddle C causes an oscillating movement of the plungers or paddles D, the paddles D approaching as the paddle C recedes. 65

The water-tight box A is inclosed with a cover H, held down by screws pivoted on the pins h and passing over or between the lugs h' . The cover is provided with a lid K, hinged on a rod or spindle k . The lid K is also provided with a small circular lid L, which can be opened readily for the insertion of small articles, as collars and cuffs in nets, which are held in position by a circle of wire at their neck of a size slightly larger than the round 75 hole. When such small articles are being done, the front opening a is entirely closed by a slide B. The box is also provided with a steam-chamber M to maintain the starch or other liquor at the desired temperature. 80 The crank-disk G, rigidly mounted on the shaft n' , is provided with the upper member of a clutch N, by which it can be thrown into and out of gear, as may be required to start or stop the machine. The lower part of the 85 clutch is fixed to and carried by a sleeve n , loose upon the shaft n' , and the lower member of the clutch is rotated by the worm-gear O. The lower member of the clutch is raised into gear by the foot-lever P, operating through 90 the forked lever p , and when the foot-lever P is released it falls out of gear again by its own weight.

When the apparatus is in operation, the box A is filled nearly up to the bottom of the 95 opening a with the starch or other liquor. The parts of the articles to be treated are introduced through the opening a , and the sliding panel B is closed down upon them. By depressing the foot-lever P the clutch is thrown 100 into gear and the plunger or paddle C is set in motion and alternately compresses the ar-

ticles against the front side of the box and releases them. The connection between the plunger or paddle C and the oscillating paddles D is such that the forward movement of plunger C causes the paddles D to recede, and the backward movement of plunger C causes them to approach, so that the paddles D compress or squeeze the articles alternately with the plunger or paddle C and in a direction at right angles thereto and at the same time without rubbing them.

What we claim as our invention, and desire to protect by Letters Patent, is—

1. In apparatus for starching shirts or other articles the combination with a water-tight receiver A provided with an opening *a* down one side through which the clothes project, of a sliding panel B, a reciprocating paddle C, two oscillating paddles D, and connecting-
20 rods *d* and *E'* by which they are connected to the shank of the paddle C, substantially as described.

2. In apparatus for starching shirts and

other articles, the combination of a water-tight receiver A provided with an opening *a* 25 down one side through which the clothes project, a sliding panel B to close the opening, a reciprocating paddle C and two oscillating paddles D in the interior of the receiver A, connecting-rods *d* and *E'* by which the paddles D are connected to the shank of the paddle C, the crank-disk G rigidly mounted on the shaft *n'* to operate the paddles, a clutch N, the movable sleeve *n*, and the levers P and *p* for placing the two members of the 30 clutch in gear, substantially as described.

In testimony whereof we have signed our names to this specification, in the presence of two subscribing witnesses, this 3d day of September, 1897.

THOMAS BOLTON GIFFEN.
JOHN BISSETT.
